UNITED STATES PATENT OFFICE.

ALBERT A. GORDON, OF WORCESTER, MASSACHUSETTS, ASSIGNOR TO THE CROMPTON & KNOWLES LOOM WORKS, OF SAME PLACE.

SHUTTLE-BINDER SPRING.

SPECIFICATION forming part of Letters Patent No. 608,038, dated July 26, 1898.

Application filed January 4, 1897. Serial No. 617,868. (No model.)

To all whom it may concern:

Be it known that I, ALBERT A. GORDON, of Worcester, county of Worcester, State of Massachusetts, have invented an Improvement in Shuttle-Binder Springs, of which the following description, in connection with the accompanying drawings, is a specification, like letters on the drawings representing like parts.

10 In looms as now commonly made the binder which acts on the shuttle in the box is acted upon by a strong flat spring. These springs are comparatively heavy, and when applied to a shifting shuttle-box their aggregate weight adds considerably to the momentum of the lay, and, further, these springs have frequently to be bent or changed in shape to adapt them to their work, so that they shall exert the desired pressure on the binder, and 20 they frequently break transversely because of the strain put on them in use.

This invention has for its object to overcome the objections above stated, and to do this I have devised a new binder-spring, it 25 consisting of wire bent to present two arms lying side by side, said new spring being very light and practically indestructible.

Figure 1 shows part of a shuttle-box presenting one cell with a binder acted upon by 30 my novel spring; Fig. 2, a view of the shuttle-box turned over from its position Fig. 1. Fig. 3 shows the spring enlarged and detached. Fig. 4 shows the spring-holder detached, and Figs. 5 and 6 show modified forms 35 of springs.

The metallic shuttle-box frame A, shown as a one-shell box, and its binder a, pivoted at a', are and may be of any usual construction commonly used in looms.

40 Instead of the usual flat steel spring bent and having a hole for the reception of a screw to confine the spring to the shuttle-box I have produced a novel spring B, it being shown as composed of wire, I having ascertained by practice that a wire spring will 45 stand up to its work and wear longer without breaking than the usual flat steel spring. This new spring is made by bending a piece of strong spring tempered wire to leave two corresponding branches b b, somewhat inclined 50 with relation each to the other, the said

branches having each an inclined portion b' and neck portions b², the neck portions being adapted to be embraced by a holder c, shown as a washer, it preferably having lips e' at 55 two of its edges, so that when said holder is set onto the neck portions of the spring and a screw c² (see Figs. 1 and 2) is put through the holder and between the two necks the said neck portions will be firmly seated and 60 held on the shuttle-box.

The branches in Figs. 1 to 3 have bent tail-pieces b³ of such shape as to prevent the ends of the branches from being drawn from between the lips c'. 65

The end of the wire spring which contacts with the binder may be variously shaped; but Figs. 1 to 3 show a preferred form, where-in the free end of the wire spring is shown bent inwardly, as at e, to make a spring-head 70 which may act against a lump e' on the binder or between projections. The tailpieces of the branches will preferably rest on a projection f from the shuttle-box, so that by turning the screw c² in more or less the pressure 75 of the free end of the spring on the binder may be increased or adjusted to the desired amount. This invention is not, however, to be limited to the use of the head e. The double-branched spring acts more readily and 80 favorably than could a one-branch spring, and the double-branched spring is far more durable than any plate-spring.

In Fig. 5 I have shown a modification where-in in the two branches h h' have their ends soldered together at h², making the head different from that shown in Fig. 3, the holder c resting on the neck portion h³. 85

In Fig. 6 I have shown another modification, wherein the wire comprising the acting 90 end or head of the spring is flattened to act on the binder, the free extremities of the two branches having the two necks b² and pointed ends b¹⁰ to enter holes in the shuttle-box.

I have herein shown a metallic shuttle-box; 95 but it will be understood that my improved spring may be used on any plain loom having one shuttle-box at the end of the lay and the spring may act on the usual binder. The wire used may be either round or of any other 100 usual shape in cross-section.

Having described my invention, what I

claim, and desire to secure by Letters Patent, | is—

1. The combination, with a shuttle-box, of a shuttle-box-binder spring composed of wire, | 5 the said spring presenting two branches, and means to confine said spring on the shuttle-box, substantially as described.
2. A shuttle-box-binder spring composed of two branches and a head uniting said branches | 10 at one end, substantially as described.
3. In a shuttle-box, a shuttle-binder spring composed of two branches, one end of said

spring acting on the binder while the opposite end thereof is retained by a holder, combined with a holder having lips, substantially 15 as described.

In testimony whereof I have signed my name to this specification in the presence of two subscribing witnesses.

ALBERT A. GORDON.
